UNITED STATES PATENT OFFICE.

WILBUR L. WRIGHT, OF FULTON, NEW YORK, ASSIGNOR TO OSWEGO FALLS CORPORATION, OF FULTON, NEW YORK, A CORPORATION OF NEW YORK.

PAPER HOOD CAP AND THE PRODUCTION THEREOF.

Application filed September 2, 1927. Serial No. 217,191.

This invention relates to paper material hood caps particularly intended for exteriorly covering or capping the heads of milk bottles and other containers that are formed 5 with exterior rims or enlargements surrounding the container mouths; and the objects and nature of the invention will be readily understood by those skilled in the art in the light of the following description of the accompanying drawings that illustrate what I 10 now believe to be the preferred mechanical expressions or embodiments of the invention from among other forms and features within the spirit and scope of the invention.

15 The particular object of this invention is to provide an annularly skirted hood cap formed of sheet paper and shaped by any suitable means or by any suitable method to provide the annular skirt with longitudinal 20 folds or creases through which the surplus paper material is taken up in the formation of the depending skirt, whereby the skirt can be contracted in diameter to provide a lower securing portion with the folds closed 25 together or contracted, and whereby the skirt, particularly the lower portion thereof can be increased in diameter by the expansion of the folds, and to provide as a part of this cap an elastic binder of a more or 30 less permanent nature that constantly tends to maintain the skirt with its lower end portion contracted and at the same time to permit expansion of the skirt when the necessary expanding force is applied thereto 35 against the tension of the binder, and particularly to provide the cap skirt with an elastic binder extending to the inner surface thereof to contact the container surface when applied and that is tacky or capable of being rendered 40 tacky to form a tight adhering seal between the hood cap and container surface and that can be stripped from the container surface.

I attain this object, by providing this sheet paper material hood cap with an elastic rubber or rubber material binder deposited on 45 and adhering to the surface or surfaces of the cap skirt usually in the form of a thin film or films or layer or layers constantly tending to hold the lower end of the skirt contracted to 50 securing form, or this binder can be in the form of elastic rubber layers formed on the skirt and elastically uniting the walls of the skirt folds to constantly tend to hold the walls together and consequently the lower

end of the skirt in contracted form, and by 55 employing such deposited or elastic material that cures or dries with a non-tacky exposed surface and one that can be rendered tacky when desired.

One desirable form of the hood cap of my 60 invention, is intended as a so-called push-on hood cap, inasmuch as the normally contracted lower or securing end of the cap skirt is of less diameter than the upper portion of the cap skirt, and hence by reason of the elasticity or rubber like quality of the soft rubber binder, this cap by rocking movement can be snapped on to the head of a bottle or other container, and by like movement in the opposite direction can be rocked upwardly and 65 slipped from the head of the bottle or the container, and whereby this push-on cap can also be made a secured tight seal cap by rendering the elastic medium tacky to tightly 70 adhere to the container surface.

75 Referring to the accompanying drawings forming a part hereof:

Fig. 1 shows in side elevation a flaring skirt paper material hood cap in its original form, the stippled surface indicating the elastic 80 adhering binder on either the inner or the outer surface of the creased or pleated skirt or on both.

Fig. 2 shows in side elevation the hood cap in its final or completed form with the elastic or soft rubber binder applied thereto and 85 yieldingly holding the lower or securing portion of the skirt contracted.

Fig. 3 is a side elevation showing a portion of a bottle and the paper material hood cap 90 in the act of being expanded by pressing and rocking onto the bottle head or therefrom.

Fig. 4 is a sectional view of a bottle head closed by the ordinary inner paper disk, and covered by the hood cap of my invention, 95 either the push-on cap or the pushed-on and sealed cap.

Fig. 5 shows in elevation a flaring skirt flexible sheet paper hood cap, such as shown by Fig. 1, with the exception that the skirt is rendered expandable by longitudinal slits dividing the skirt into tongues that serve the purpose of the longitudinal creases or folds of Fig. 1, although this slotted skirt form of cap can also have longitudinal pleats or folds 100 to take up surplus material.

Fig. 6 shows in elevation the cap of Fig. 5 with the securing portion of its slotted skirt

yieldingly held in contracted form by the normally non-tacky elastic rubber-like binder elastically holding and securing together the overlapping tongues of the slitted skirt and 5 the walls of any tucks or pleats in the skirt.

In the drawings, I show part of a container, such as a glass milk bottle, having an internal seat adapted to be closed by the ordinary paper disk *a*, as will be well understood by 10 those skilled in the art. The head of this bottle is formed with an upwardly and downwardly curving or rounding exterior annular rim 2 that provides a downwardly facing shoulder.

15 The paper hood cap is formed by dies or is otherwise pressed up from flat sheet paper to form the flat imperforate central top wall 5 and the annular depending skirt 6, and this skirt is formed in the operation of produc-

20 ing the cap, into a multiplicity of vertical or longitudinal folds, tucks or pleats 7 of any suitable or desirable form in cross section, and/or longitudinal slits 7', to form tongues, preferably so that the pleats or folds can 25 be more or less tightly closed together and if need be overlapped in flat form annularly around the skirt, when the skirt is in its contracted form. When the skirt is expanded to 30 slip onto or from the bottle head these folds or pleats expand or the tongues spread.

To normally and yieldingly maintain, particularly the lower or securing end of, the skirt in contracted form tightly hugging the downwardly facing shoulder or underside of 35 the bottle head rim, I provide the elastic binder 8, consisting of an adhering surface film or films or layer or layers of elastic rubber or rubber like binder formed on and carried by the cap skirt. This elastic binder 40 constantly tends to yieldingly hold the skirt folds or pleats in collapsed condition or the tongues overlapping and the annular securing portion or end of the skirt in contracted hood cap securing form. This rubber binder 45 is of such elastic quality as to permit the skirt to radially expand under tension so that when released the skirt will snap back or spring back, under the tension of the elastic binder to securing condition.

50 This binder is formed on and adheres to the paper skirt, substantially as a permanent part thereof, by applying to the skirt a liquid composition consisting of any suitable solution of rubber or latex, any suitable filler 55 or fillers, and a suitable solvent such as ammonia or the like. Such emulsified latex or solutions are well known and familiar to those skilled in the rubber industry, and I particularly employ such a latex solution or 60 emulsion that will dry or cure to produce a soft dry non-tacky elastic film of rubber on and adhering to the paper to perform the functions hereinbefore described. Such rubber solutions include a solvent or solvents of 65 liquids that evaporate to cause curing or dry-

ing of the deposit of latex and other solid ingredients as a dry waterproof non-tacky film on and closely adhering to the paper and possessing the rubber like quality of elasticity, of stretching under tension, with a constant tendency to return to its original form. The emulsified rubber or solution can be applied to the entire inner and outer surfaces of the sheet paper cap or to either the inner 70 or outer surface thereof, or to either the inner or outer or both surfaces of the skirt alone, by dipping, spraying, or otherwise applying the rubber carrying liquid. The rubber carrying liquid is applied, preferably, while the lower or securing end of the skirt of the cap 80 is held in contracted form and the cap skirt is preferably thus held in contracted form until the rubber cures to form the soft permanent elastic film.

On the other hand the cap skirt might be 85 coated with the rubber carrying solution while the skirt is in flaring form and then the skirt can be brought to contracted form, to cap securing form, while the rubber is still tacky and uncured, so that the rubber 90 film will become set and cured while the skirt is maintained in contracted form, and thus yieldingly maintain the skirt in contracted form and cause the same to return to such form 95 when expanded to slip over the bottle head. 95

The rubber film can form an unbroken annular layer or ring around the inner or outer or both surfaces of the securing portion of the cap skirt and/or can form elastic adhering layers between the adjacent or opposite 100 walls of each pleat or fold in the skirt.

If desired sulphur or other vulcanizing agents and any well known vulcanizing accelerator can be included in the rubber emulsion or solution if it is desired to vulcanize 105 the rubber film carried by the cap skirt, at the factory, before the caps are shipped to the user.

Also instead of natural latex I can employ rubber substitutes or synthetic rubber wherever found desirable or suitable for my purposes. 110

Where the rubber film or layers are formed on the inner surface of the cap skirt it will be found that the rubber forms an approximately tight seal in contact with the glass surface of the bottle hood cap, and yet such rubber can be stripped from the glass surface as the hood cap is removed, without leaving objectionable deposits. 115

The thickness of the rubber deposit or film on the hood cap skirt while usually but a few thousandths of an inch in thickness can be controlled by the viscosity of the rubber emulsion or solution or by the number of dippings or applications of the solution to the paper. The thickness of the rubber deposit on the paper can be varied to suit conditions and the strength of the rubber deposit required for 125 varying capping conditions. 130

The paper hood cap described having the contractile elastic skirt having the permanent adhering deposit of elastic, such as rubber, binder, thereon yieldingly holding the lower or securing portion of the skirt contracted to securing position, constitutes a highly desirable push-on cap. These caps can be supplied to the market, in nested form if so desired, and can be readily separated from the nest and pushed or snapped onto bottle heads by hand or by machinery. These caps can be nested because of the elastic expandable characteristics of their skirts, and when separated from the nest, the skirt of each cap will contract to its normal form.

The cam-like or rounded surfaces of the bottle rims, facilitate the expansion of the skirts as the caps are rocked onto and rocked from the bottle heads or mouths.

20 The elastic lower or securing ends of the skirts will tightly grasp the bottle heads at the under surfaces of the rims of the heads and will thus retain the caps on the bottle heads during handling.

25 It is within the scope of this invention to provide flaring skirt flexible sheet paper caps, having the non-tacky elastic rubber binder deposits thereon, the rubber preferably not being vulcanized to such an extent as to prevent the binder surface from being rendered tacky at the hood capping situation. These flaring skirt caps can then be shipped to the bottlers who can center the flaring caps on the bottle heads by machinery, and then by 30 machinery through the use of suitable clamping or contracting heads, these flaring skirts can be contracted to securing position under the bottle head rims and then by said heads subjected to a temperature that will render 35 the binder surface tacky, particularly where the binder is made up from reclaimed rubber which is previously vulcanized rubber or where the soft rubber includes, say, a vulcanizing agent and a low temperature accelerator. The caps with the rubber binder 40 thus treated will thus adhere to and be secured and sealed on the bottle head, and can be readily removed by application of sufficient pressure to stretch the skirt and binder 45 or sever the skirt and binder to break the seal. It will be found that such cap skirts and rubber binder will strip from the glass surfaces without leaving objectionable deposits thereon.

50 I particularly desire to protect that feature of my invention involving the sealing of the hood cap skirt to and annularly around the exterior of the container, preferably below the rim or exterior of the container head, 55 by the use of a rubber or an elastic rubber like film or layer or layers on the inner surface of the hood cap skirt, possessing the characteristics of adhering closely to both the paper surfaces of the hood cap and to the glass or 60 paper surfaces of the container to form an

approximately liquid and air tight seal, and of stripping from the container surfaces without leaving thereon seriously objectionable deposits, when the hood cap is stripped or removed from the container head.

70 It is within my invention to render the depending annular skirt of the paper hood cap, before it receives the elastic rubber or rubber like film or layer or layers, expandable and contractile by pleats or folds as hereinbefore described, and/or by forming longitudinal slits in the skirt to provide the skirt with depending tongues which will overlap each other to a greater or less extent when the skirt is molded to the bottle neck under the 75 bottle rim. The rubber-like film or layer will cause these overlapping tongues to adhere together and the webs, layers or films of rubber connecting such tongues of the slitted skirt will elastically stretch to permit expansion 80 of the skirt and to return the skirt to and yieldingly maintain the same in contracted condition.

85 The feature of my invention particularly emphasized herein, is the capacity of the push 90 on elastic skirt hood cap, herein described, to perform, if so desired, the added functions of a bottle sealing cap i. e. to be tightly sealed to and secured on the exterior surfaces of the bottle head, through the medium of one 95 or more added operation steps. In other words, the push-on hood cap having layer or layers or a film or films of substantially non-tacky elastic rubber exposed at the inner surface or surfaces of its expandable skirt and 100 holding that skirt yieldingly contracted to securing condition, can also serve the purpose of a securing sealing cap by treating the rubber or rubber-like material on its skirt to soften the surface thereof and render the 105 same tacky at the hood capping situation so that the skirt on being molded, pressed or wiped to tight (preferably air excluding) contact with the exterior surfaces of the bottle head, will closely adhere thereto and seal 110 against the same, with the capacity of stripping from said surfaces when the cap is removed.

115 It is also within the scope of my invention, to provide hood-cap-forming flexible paper disks having the non-tacky elastic rubber or rubber-like films on the inner surfaces thereof, or flaring skirt paper hood caps having such films or layers on the interior surfaces thereof, and to thus supply such disks or caps to the bottlers. The bottlers at the hood capping situation, will by suitable treatment render the surfaces of the rubber films soft and tacky and then by suitable machinery 120 form the disks into hood caps on and molded and adhering to the bottle heads or mold and compress the cap skirts to the bottle heads to adhere and seal thereto.

125 The rubber films can be rendered soft by application of heat to the disk or cap while on 130

the bottle head, through the medium or rings or the molding or compressing heads that mold and compress the disk or cap on the bottle head, the disk or cap just before application can be passed through a hot chamber, or a steam chamber to render the rubber surface tacky, or the rubber surface can be rendered tacky by fumes of a rubber solvent, or by spraying with a rubber solvent, such as ammonia or the like.

The rubber film or layer can be cured or dried on the cap or disk, after application of the rubber liquid by spraying, immersing, or otherwise.

15 The following is an example from among other various rubber or rubber-like solutions, that might be employed for my purposes, namely ;—

About 50 pounds reclaimed rubber.

20 About 5 gallons gasoline.

About 10 gallons benzol with or without.

About 25 pounds CaCO_3 , precip. (calcium carbonate).

This case is in part a continuation of my 25 application filed August 20, 1927, Serial No. 215,011, for hood caps, for milk bottles and like containers.

What I claim is:

1. In the method of producing binder carrying flexible sheet paper material hood caps, those steps which comprise depositing a rubber emulsion or solution on the annular radially expansible hood cap skirt and permitting the same to cure to form an elastic permanent adhering binder.

2. In the method of producing a paper material hood cap having an annular skirt rendered expansible and contractile by longitudinal folds or pleats or tongues, that step 40 which consists in providing the skirt with an annular elastic adhering binder by depositing thereon rubber or its equivalent in the form of solution or emulsion.

3. A hood cap for container heads comprising sheet paper wherein the annular skirt of the cap is formed with longitudinal folds or pleats or tongues to render the cap expansible, the skirt of said cap being provided with a permanent elastic binder consisting of a deposit or deposits of rubber or its equivalent cured or dried on and adhering to the paper material surface and capable of stripping from glass surfaces.

4. A paper material hood cap having a normally contracted elastic expansible annular skirt provided with and carrying a normally non-tacky elastic rubber-like binder capable of being rendered tacky at the hood capping situation said binder being in dried film-like form permanently adhering to the paper material surface.

5. A flexible paper material hood cap having a radially expansible annular skirt the lower or securing portion of which is yielding- 65 ly maintained in securing form and provided

with and carrying an elastic binder composed of a deposit of rubber dried on and permanently adhering to the paper material surface and capable of being rendered tacky at the hood capping situation and of stripping from glass.

6. The method of applying to containers, a cap produced in accordance with claim 1, which comprises rendering said binder tacky at the containing hood capping situation and 75 molding the skirt having the tacky binder to the container into close adhering sealing relation on and against the surface thereof.

7. A flexible sheet paper hood cap disk having its skirt provided with a binder of 80 elastic rubber or rubber-like material deposited and dried on the paper surface and permanently adhering thereto and capable of being rendered tacky or adhering to and stripping from the container surface.

8. The method of applying flexible sheet paper hood caps having the container contacting surfaces of their skirt portions carrying a non-tacky elastic rubber-like binder deposited and cured on the paper surface and adhering thereto, those steps which consist in rendering such binder tacky by subjecting the same to heat or a solvent, at the container hood capping situation, and before or after the hood cap has been placed on the container head, and molding or contracting the hood cap skirt around the bottle head with its tacky binder in close adhering sealing contact with and around the container surface.

9. A sheet paper material push-on hood cap 100 for covering container heads, having a normally contracted elastic expansible annular skirt provided with a binder normally maintaining the skirt in contracted form and rendering the skirt expansible, said binder embodying an adhering elastic deposit of rubber like material dried thereon.

10. A hood cap for container heads, embodying flexible sheet fibrous material having the surplus material in its annular skirt 110 taken up by longitudinal folds, said skirt having an elastic binder deposit dried thereon and adhering thereto and normally holding the securing portion of the skirt in contracted form and rendering such skirt expansible for pushing onto a container head, said binder embodying rubber like material applied to the skirt in liquid form.

11. A flexible paper material hood cap having a radially expansible annular skirt the securing portion of which is yieldingly maintained in contracted securing form by and provided with an elastic deposit dried thereon to substantially non-tacky condition and embodying rubber latex.

12. A sheet fibrous material hood cap for container heads having its annular skirt longitudinally creased to render the same radially contractile and expansible, said skirt having a dried adhering deposit of rubber 130

latex entering into said creases and rendering said skirt radially expansible and normally maintaining the same contracted.

13. A paper hood cap disk, the annular skirt portion of which carries at its bottle contacting inner surface at least an approximately non-tacky rubber like elastic binder adhering to the paper, and capable of being rendered tacky for sealing said skirt portion to the bottle contacting surface for stripping therefrom to remove the cap.

14. A sheet paper hood cap having its an-

nular skirt formed with longitudinal folds to take up the surplus material and render the skirt radially expansible and contractile, said skirt provided around the circle thereof with an elastic binder that embodies deposits of elastic rubber like material within said folds and adhering to the adjacent side walls thereof.

In testimony whereof I have hereunto set my hand at Fulton, New York, this 30th day of August, 1927.

WILBUR L. WRIGHT.
